(57) **CLAIM**

The ornamental design for a floor mat hanger as shown and described.

DESCRIPTION

FIG. 1 is a front perspective view of a floor mat hanger according to an embodiment of the disclosure;

FIG. 2 is a front plan view thereof;

FIG. 3 is a rear plan view thereof;

FIG. 4 is a left side plan view thereof;

FIG. 5 is a right side plan view thereof;

FIG. 6 is a bottom plan view thereof;

FIG. 7 is a top plan view thereof;

FIG. 8 is a front perspective view of a floor mat hanger according to another embodiment of the disclosure;

FIG. 9 is a front plan view thereof;

FIG. 10 is a rear plan view thereof;

FIG. 11 is a left side plan view thereof;

FIG. 12 is a right side plan view thereof;

FIG. 13 is a bottom plan view thereof;

FIG. 14 is a top plan view thereof;

FIG. 15 is a front perspective view of a frame for the floor mat hanger shown in FIG. 1 or FIG. 8, shown removed from other structures for illustration;

FIG. 16 is a front plan view thereof;

FIG. 17 is a rear plan view thereof;

FIG. 18 is a left side plan view thereof;

FIG. 19 is a right side plan view thereof;

FIG. 20 is a top plan view thereof; and

FIG. 21 is a bottom plan view thereof.

FIG. 22 is a front perspective view of a cover for the floor mat hanger shown in FIG. 1 or FIG. 8, shown removed from other structures for illustration;

FIG. 23 is a bottom perspective view thereof;

FIG. 24 is a front perspective view of a hook for the floor mat hanger shown in FIG. 1, shown removed from other structures for illustration; and,

FIG. 25 is a front perspective view of a hook for the floor mat hanger shown in FIG. 8, shown removed from other structures for illustration.
